COMBINATION BROOCH AND CLASP

Ralph Polcini, New York, N. Y.

Application February 1, 1936, Serial No. 61,862

3 Claims. (Cl. 63—20)

This invention relates broadly to jewelry and particularly to brooches with detachable parts in the form of independent ornamental clasps which may be employed either individually or in pairs for a multitude of uses.

The principal object of my invention is to provide an attractive, fool-proof and useful article of this kind, which is not only pleasing in appearance, but is extremely simple and practical in construction, requires no special care or intricate handling, will not catch or become entangled with garments, and which device, due to its great simplicity, may be manufactured at a fraction of the cost of heretofore produced similar articles. Another object of my invention is to so construct the component parts of my device as to readily facilitate the attachment of the clasps to, or their removal from the frame, irrespective of the position at which they are first introduced thereinto.

The foregoing and still other objects and advantages of my invention will become more clearly apparent from the following description in connection with the accompanying drawing, which latter forms part of my invention, but which is not intended to restrict me to the specific forms shown. In the drawing

Fig. 1 is a front elevation of my device in assembled form.

Fig. 2 is a rear elevation of my flat rim-frame for supporting clasps.

Fig. 3 is a longitudinal cross-sectional view through the rim-frame, taken on lines 3—3 of Fig. 2.

Fig. 4 is a rear elevation of one of my clasps, with its snap member in closed position.

Fig. 5 is a side view thereof.

Fig. 6 is an end view of my clasp showing the abutting end thereof.

Fig. 7 is a section through an open clasp in the plane indicated by lines 7—7 of Fig. 6, and Fig. 8 is a longitudinal section, enlarged, through a partially assembled brooch.

Referring now specifically to the figures, number 10 denotes clasp bodies, having ornamental front faces 11 of any desired pattern, and substantially flat, straight back faces 12. At the center of the straight abutting end of each of the clasp bodies there is provided a recess or pocket 13, the purpose of which will be explained presently. A depression 14 is formed at the back face of the body near its outer end.

Disposed substantially parallel to the abutting edge of the body, cast into, and extending from its back face, and bridging recess 13, is a hinge

element 15, having two parallelly disposed, perforated end-lugs 16 and central lug or extension 17 disposed midway between end-lugs or ears 16 and substantially at right angles to the latter.

In engagement with the perforations of ears 16 are pintles of snap member 18, forming an essential, and the operative part of the clasps. This snap member comprises a stamping made of resilient material, the body of which is cut by two slots to produce a central spring element 19, which latter constantly and tensionally engages, and bears against central extension 17 of hinge element 15. Through the cooperation between spring 19 and extension 17, the snap member is held under tension in either closed position, that is substantially parallel to the back face of the clasp member, or in its open position, or at right angles to the back face 12.

Extending from the engaging or inner face of the snap member, and substantially at right angles thereto, are provided numerous prongs 20 stamped out from the material. They serve for engaging garments or other articles when the clasps are used individually. One of the prongs, marked 20, is near the free end of the snap member and has a special function which will be explained later on. All of the prongs are preferably clustered together, and in order to prevent them from becoming dull through contact with the clasp body, I have provided cut out or recess 25 30 35 40 45 50 55 60 65 9860 9865 9870 9875 9880 9885 9890 9895 9900 9905 9910 9915 9920 9925 9930 9935 9940 9945 9950 9955 9960 9965 9970 9975 9980 9985 9990 9995

tially parallel thereto, as may be seen in Figures 3 and 8.

The upper, lesser curved frame portion 21 has symmetrically disposed exterior lugs 27, to which 5 are secured supports of attaching pin 28, one end of which is hinged at post 29, while its other end engages a safety catch in post 30.

When a clasp is to be attached to the frame, its hinge element 18 is swung to its open position, shown in Figure 7, and is placed into one 10 of the loops formed by the frame. The insertion is naturally made from the frame face opposite to that to which pin 28 is attached. Now the clasp body is turned so that lug 26 enters 15 into and engages recess 13. When that is done the back face of the clasp body overlies and abuts with the exterior face of the frame. Now hinge element 18 is snapped down to its closing 20 position, at which prong 20 will register with and engage end-notch 24 of the frame. It will be observed that the abutting end of the body covers and overlies half of the width of bar 25.

When the second clasp is to be attached, the 25 same simple procedure is followed. The cooperation on one hand of lugs 26 with recesses 13, and the bridging portion of hinge element 15, and the co-action between prongs 20 and notches 24 on the other hand, bring about a very simple, but nevertheless an absolutely positive and effective interlocking between the frame and the 30 clasps, which are prevented from bodily moving relative to the frame in any direction.

While I have shown and described specific 35 forms of my invention, it is quite obvious that changes and improvements necessitated by style demands and other reasons may be readily made, and I therefore reserve for myself the right to such modification within the scope of my invention, as set forth in the annexed claims.

40 I claim:

1. In an article of the class described, a substantially oval rim-frame provided with a solid 45 median bar connecting the lesser curved portions thereof, a pair of lugs extending symmetrically from the center of said bar and being off-

set relative to the plane of the frame, inwardly opening end-notches symmetrically located at the acutely-curved portions of the frame, a pair of ornamental clasps overlying said frame face to face and concealing it and being removably connected therewith, recesses provided at the abutting edges of said clasps for accommodating and engaging the lugs of said median connecting bar, snap members, forming operative parts of said clasps and provided with a plurality of prongs, 10 one of which prongs of each snap member registers with the responsive end-notch of the frame. 5

2. In an article as in claim 1, and wherein the rim-frame is provided with outward extensions at one of its lesser curved portions, and an attaching pin operatively secured to said extensions. 15

3. In an article of the class described, a relatively light, elongated, substantially flat and plain rim-frame, a centrally located single bar connecting the breadth of the frame, a pair of symmetrically arranged lugs extending from the centre of the bar towards the ends of the frame and being off-set and substantially parallel to the horizontal plane of the frame; inwardly opening, 20 symmetrically arranged notches provided at the ends of the frame, a clasp removably associated with the frame and comprising a body having an exterior ornamental face and a substantially flat back face overlying and contacting one face of said frame, one end of said body adapted to contact with and to cover substantially half of the width of said connecting bar, a centrally located recess or pocket provided in said one end of the body for normally accommodating and engaging one lug of said bar, a snap member operatively connected with the back of said body and provided with a prong, the latter normally engaging one of the notches of the frame, said pocket and said bar lug, and said snap member 30 prong and said frame-end notch, cooperating 35 in such a way as to prevent disengagement of the clasp from, and its movement relative to said frame. 40

RALPH POLCINI. 45
